(57) **CLAIM**

We claim the ornamental design for a stacking chair, as shown and described herein.

DESCRIPTION

FIG. 1 is a front, elevational view of a first embodiment of the stacking chair;

FIG. 2 is a right-side elevational view of a first embodiment of the stacking chair;

FIG. 3 is a rear elevational view of a second embodiment of the stacking chair;

FIG. 4 is a top plan view of a first embodiment of the stacking chair;

FIG. 5 is a front, top, right-side perspective view of a first embodiment of the stacking chair, the opposite side being a mirror-image thereof;

FIG. 6 is a rear, top, right-side perspective view of a second embodiment of the stacking chair, the opposite side being a mirror-image thereof, and,

FIG. 7 is a front, top, right-side perspective view of the first and second embodiments of a stacking chair in stacked relationship.

The undersides of the stacking chairs have not been shown and form no part of the claimed design.
